REFRIGERATOR DOOR

Gebhard C. Bohn, St. Paul, Minn., assignor to
 The Bohn Company, St. Paul, Minn., a corpora-
 ration of Minnesota

Application April 14, 1928, Serial No. 270,014

4 Claims. (Cl. 20—35)

My invention relates to improvements in doors, particularly designed for refrigerators, wherein the door body has an exterior metal covering.

Among the objects of my invention is to provide a door construction, wherein the door backing may be interlocked with a metal exterior covering, preferably exteriorly coated as with enamel, lacquer, duco, etc., without exposed screws, or other fastening means, extending through the covering, other than the fastening means of the regular hardware; to provide a door backing unit which will permit being easily separated from the metal covering, without injury to either the covering or the backing; to provide a door backing unit which will be adjustable in its locking connection with the door covering to make up for inaccuracies in either the backing element or metal covering; and to provide a door backing which may be put together as a built-up unit before being interlocked with the door covering and thus secure the maximum of strength, rigidity, etc.

In the accompanying drawings forming part of this specification:

Figure 1 is an exterior plan view of a door constructed in accordance with my invention, with the door covering shown partly broken away to better show part of the locking connection between the door backing and covering.

Figure 2 is a section on line 2—2 of Figure 1; and

Figure 3 is a perspective view of the door, showing the backing and door covering in the initial step of being interlocked.

Referring to the drawings, A represents a door body or backing, and 2 a metal plate forming an exterior covering or sheathing for the door, this plate being usually coated with enamel, porcelain, or other material which would be subject to injury, as chipping. The edge 3 of the plate 2 is 40 interturned to form a channel to receive locking means carried by the door body, as hereinafter set forth.

The door body or backing, as shown, is built up of strips 4 connected to make a framework that will fit within the space upon the back of the door formed by the interturned door edges 3, and to form a space or chamber between the strips to receive insulation 5. The inner face of the door backing is covered, as by an enameled metal plate 6, having interturned edges fitted into grooves 7 in the door backing. In order to provide for a resilient contact with the refrigerator body, resilient gaskets 8 are secured around the edge of the strips 4, so that the head 9 of the gasket 55 will stand outside the edge of the door covering

when the door covering and backing are locked together, and make contact with the exterior body of the refrigerator. That portion of the backing strips 4 to which the gasket 8 is secured, is inwardly beveled to make up for the thickness of the gasket in permitting the door backing to fit tightly between the interturned edges of the door covering. A second gasket 10 is secured to the door backing between the gasket 9 and the inner face of the door, as by being secured between moldings 11 and 12, forming a part of the door backing, the bead 13 of the gasket 9 projecting beyond the moldings to make contact with the inner jamb of the door opening. The molding 12, as shown, also extends over and covers the edge of the inner plate 6 of the door backing.

Secured to the inner face of the door backing, at one side thereof, as by screws 14, are the outwardly projecting metal fingers 15, the metal fingers having inwardly turned free ends 16 adapted to fit into the adjacent channel of the door covering, as shown particularly in Figure 2. The side of the door backing opposite to the locking fingers 15 is secured in position, as by screws 17, passing through the metal door covering and into the door backing. The screws 17 are covered by the door hinges 18, which hinges are secured upon the exterior of the door in the ordinary manner, as by means of screws 19. Resilient gaskets 20 interposed between the edges and the door covering keep the metal hinges out of injuring contact with the door covering.

The door backing and the metal outer covering or sheathing are placed together, as illustrated in Figure 3, by first hooking the locking fingers into the channel in one side of the door covering, then swinging the door backing into position against the door covering and securing the free edge of the door by the screws 17 inserted through the door covering and into the body of the door backing.

By the features of construction shown and described, I secure many important advantages. The problem of securing a thoroughly satisfactory closure in a refrigerator, wherein the refrigerator body and door is to be covered by enameled metal sheets, is one that I, as a manufacturer of refrigerators, have been, through years of experimentation, working out a proper solution of.

It is desirable, for instance, that no exposed fastenings, as screws or nails, shall pass through the enameled covering plate of the door, other than the fastenings of the standard hardware. It is desirable, further, to secure a door backing

that can be very easily and without injury to either the backing or the covering separated from the covering by the user, so that the user, in case the enamel covering becomes chipped or injured, may simply order another enamel covering that can be quickly fitted to the backing in substitution for the damaged one, or, may be in the same position with reference to the door body or backing.

10 It is desirable that the backing be of particularly solid character, and not to have joints that will separate or otherwise be damaged or become loosened or separated from the metal sheathing in the very severe shocks to the door, resulting from the slamming of the door.

15 It is desirable that the backing and sheathing be so constructed and co-operatively fitted together, that inaccuracies in the construction of either the door body or covering may be compensated for.

20 It is desirable that a very tight construction be secured to be in the greatest possible degree moisture proof.

25 It is desirable that the contact elements between the door and body of the refrigerator be so supported, not only as to prevent injury to the enameled surfaces of the refrigerator body, but, where resilient gaskets, as herein shown, are employed, those gaskets should be protected to the maximum degree, and also be capable of being very easily removed where damaged and new ones substituted.

30 By having the door backing made up as a unit member before being placed in connection with the door covering, I am enabled to secure a very solid and permanent construction of backing. It enables me to firmly glue or dovetail the wooden members of the backing together, avoiding joints into which moisture might otherwise pass, and giving the maximum of strength and rigidity to the construction.

35 In building doors of this type, it is difficult to get the covering plates with their turned edges of an absolutely uniform character and the same with reference to the door backing itself, but, in the above described construction it will be apparent that any inaccuracies in the construction of the door backing, or in the sheathing plate, are compensated for by the adjustability of the locking fingers within the channel of the sheathing plate. Furthermore, by having the edges of the door backing which support the gaskets 40, inwardly beveled, and the compressible gaskets secured to the beveled edge, the thickness of the 45 gasket inside the bead is compensated for and a grip is secured upon the compressible gasket between the inturned edge of the door covering plate and the backing.

50 In using the word "enameled" in the claims in this case, I am using it in the general sense of covering a coating upon the sheathing plate subject to injury as by chipping by contacting

5 metal parts. Such coating may be of a baked, vitreous material, enamel, lacquer, duco, etc., that needs to be protected against the injury of contacting metal.

I claim:

1. A door construction of the class described, including an exterior enameled sheathing plate formed with an inturned edge constituting a channel, a wooden backing unit constructed on one side to fit into the adjacent channel, a separable connection between the opposite side of said unit and the sheathing plate, and a compressible gasket secured around the base of said door unit to be gripped between said unit and the in-turned edge of the door sheathing, said gasket 15 projecting beyond said inturned edge.

2. A door construction of the class described, including an enameled sheathing plate formed with an inturned edge, a backing member chambered to receive insulation, one side of said backing member interlocking with the groove formed by the adjacent inwardly turned edge of the sheathing plate, means detachably connecting the other side of the backing member and the sheathing, a projecting gasket secured around 25 the base of the backing member to be gripped between the backing member and the inturned edge of the sheathing plate, and a second projecting gasket supported by the backing member intermediate of said first mentioned gasket and the 30 inner face of said backing member.

3. A door construction of the class described, including an exterior enameled sheathing plate formed with an inturned edge, constituting a 35 channel, a wooden backing unit fitted within the space intermediate the inturned edges of said plate, a member projecting from one side of said unit into the channel formed by the adjacent in-turned edge of the plate, fastening means passing through the sheathing plate and into the opposite side of said backing member in co-operation 40 with hinges secured to said sheathing plate and covering the fastening means passing through the sheathing plate into the backing, and a gasket separating said hinges from the enamel 45 surface of said plate.

4. A door construction of the class described, including an exterior sheathing plate formed with an inturned edge, a backing unit constructed to fit against said sheathing plate and against 50 said inturned edge, means projecting from one side of said backing unit into a channel formed by the adjacent flange of the sheathing plate, the opposite side of the unit being freely swingable past the adjacent flange of the sheathing into 55 contact with the sheathing plate, the base of the freely swingable unit adjacent the flange of the sheathing plate being inwardly beveled, supporting hinges for said door, and fastening means extending through said hinges and into the freely 60 swingable side of the backing unit.

GEBHARD C. BOHN.
